CIRCUIT BREAKER

Oswald von Mehren, Lorain, Ohio, assignor to
Westinghouse Electric Corporation, East Pitts-
burgh, Pa., a corporation of Pennsylvania

Application July 9, 1946, Serial No. 682,195

14 Claims. (Cl. 200—108)

1

This invention relates to circuit breakers and more particularly, to circuit breakers of the type that are tripped instantaneously on overload currents above predetermined values and after a time delay on lesser overload currents.

One object of the invention is to provide a circuit breaker with an improved electromagnetic trip device having a tripping armature and a time delay means which has no mechanical connection to the tripping armature.

Another object of the invention is to provide a circuit breaker with an improved electromagnetic trip device having a movable tripping armature and a hermetically sealed time delay device magnetically connected to the armature for delaying tripping operation of the armature.

Another object of the invention is to provide a circuit breaker with an improved electromagnetic trip device having a movable tripping armature and a time delay device disposed in a hermetically sealed casing for delaying tripping operation of the armature, said armature being disposed externally of said hermetically sealed casing.

Another object of the invention is to provide a circuit breaker having an improved electromagnetic trip device according to the preceding paragraphs with means for preventing false operation of the trip device in response to sudden shocks or jarring forces.

Another object of the invention is to provide a circuit breaker with an improved trip device, time delay means and shock proof device according to the preceding paragraphs all of said devices being readily removable as a unit without disconnecting the moving parts.

The novel features that are considered characteristic of the invention are set forth in the appended claims. The invention itself, however, both as to structure and operation, together with additional objects and advantages thereof will be best understood from the following detailed description of one embodiment thereof when read in conjunction with the accompanying drawing, in which:

Figure 1 is a side elevational view, partly in section, of a circuit breaker embodying the invention, and

Fig. 2 is a front elevational view of the trip device with the scale plate partly broken away for clearness.

Referring to Figure 1 of the drawing, the reference numeral 11 designates a base of strong insulating material which supports the various parts of the circuit breaker. A pair of terminals 13

2

and 15 are suitably secured to the base and each terminal has one or more connecting studs 19 which extend through the back of the base 11 and serve to electrically connect the breaker to the circuit which it controls.

The upper terminal 13 has a contact block 21 of rigid conducting material secured thereto; and a rigid contact block 23 secured to the base is electrically connected to the lower terminal 15 through the energizing winding of the trip device of the breaker, which will be hereinafter described.

The contact means and mechanism of the circuit breaker illustrated are similar to the circuit breaker fully disclosed in Patent No. 2,214,471 issued September 10, 1940 to Leon R. Ludwig and Merle E. Horn, and assigned to the assignee of the present invention. Hence only a brief description of these parts will be given in this application.

The main stationary contacts 25 and 27 are rigidly secured to the contact blocks 21 and 23, respectively; and the auxiliary stationary contacts 29 and 31 are secured to a triangularly-shaped contact platform 33 of conducting material which is mounted on the upper portion of the block 21 for limited tilting and rocking movement by means of pins 35 projecting from the opposite sides of the platform which engage in slots 37 provided in a pair of side walls 39 secured to the block 21. The platform 33 is biased outwardly from the base 11 by a plurality of springs 41 and 43, and outward movement of the platform is limited by the engagement of the pins 35 with the outer ends of the slots 37 and by stop projections 45 carried by the platform adjacent its upper end. The platform 33 and, consequently, the auxiliary contacts 29 and 31 are electrically connected to the terminal 13 by means of a flexible shunt conductor 47.

The movable contact means of the circuit breaker comprises a channel-shaped contact arm 49 of conducting material which is rigidly secured to a pivoted switch member 51 by means of a plurality of screws 53. The contact arm 49 carries a main contact bridging member 55 for bridging the main contacts 25 and 27, and an auxiliary contact member 57 for engaging the stationary auxiliary contacts 29 and 31, the auxiliary contact member 57 being secured to the upper end of the channel-shaped contact arm 49 by a plurality of screws 59.

The main contact bridging member 55 is formed of rigid conducting material, and is loosely mounted on the contact arm 49 for lim-

ited movement relative to the contact arm toward and away from the main contacts 25 and 27 by means of a pair of studs 61 secured to the contact carrying arm 49, only one stud 61 being shown. A pair of coil springs (not shown) encircle the studs 61, and are disposed between the contact carrying arm 49 and the bridging member 55 for biasing the bridging member toward the stationary main contacts 25 and 27 with a predetermined force. The ends of the bridging member 55 are beveled to lie parallel with the beveled edges of the contact blocks 21 and 23, and have a pair of contacts 67 secured thereto for engaging the main stationary contacts 25 and 27.

The auxiliary contact member 57 is formed of rigid conducting material, and has an intermediate contact 69 and an arcing contact 71 secured thereto for engaging the intermediate and arcing contacts 29 and 31 of the stationary contact means.

A flexible shunt conductor 73 electrically connects the auxiliary contact arm 49 to the main stationary contact block 23. The flexible conductor 73 has its upper end secured to the contact arm 49 by the lower bolts 53. The lower end of the flexible shunt conductor 73 is secured to the lower contact block 23 by means of a bolt 77.

The switch member 51 has a yoke-shaped lower end which is pivotally mounted between the side walls of a main frame 79 by means of a pivot pin 81. The switch member 51 is movable about its pivot axis to open and closed circuit positions to open and close the contact means of the breaker by means of an operating mechanism indicated generally at 83.

The operating mechanism 83 is supported by the main frame 79 and comprises an actuating lever 85 pivoted on a pin 87 carried by the frame, and is connected to the switch member 51 by a link 89. An operating member 91 is also pivoted on the pin 87 for movement about the same axis as the actuating lever 85. The actuating lever 85 is normally and releasably connected to the operating member 91 for movement thereby by means of a pair of latches 93 and 95, which are pivotally mounted on the lever 85 at 97 and 99, respectively. The latch 93 engages a roller 101 carried by the operating member 91, and this latch is, in turn, held in latching position by the auxiliary latch 95. The operating member 91 is adapted to be releasably held in closed circuit position by means of a main holding latch 103 pivoted at 119, which releasably engages the roller 101. The auxiliary latch 95 is provided with a curved tailpiece 105 by means of which it is released to cause release of the latch 93 and consequent tripping of the circuit breaker by the release of the actuating lever 85 from its connection with the operating member 91. When released the actuating member 85 moves in a counterclockwise direction about the pivot axis 87, causing opening of the movable contact means. During this movement, a cam surface 107 of the lever 85 engages the beveled nose of the main holding latch 103, moving the holding latch to released position to effect release of the operating member 91. The switch member 51 and the actuating lever 85 are biased to open position by means of a pair of accelerating springs 109 (only one being shown), which are connected at their upper ends to the switch member 51 and at their lower ends to the sides of the main frame 79.

To close the circuit breaker after it has been tripped open, the operating member 91 is first moved in a counterclockwise direction about the pivot axis 87 to the open position to effect resetting of the latches and reestablishment of the releasable rigid connection between the actuating lever 85 and the operating member 91. After the rigid connection is thus established, the operating member 91 is moved in a clockwise direction to closed position by means of a handle 111 to effect closing of the contact means of the breaker. The clockwise or closing movement of the operating member 91 is limited by a portion 92 thereof striking a fixed stop 94 on the frame 79. When the parts have been moved in closed position, the main holding latch 103 reengages the roller 101 to hold the operating member in closed position. The stop 94 is located to permit a slight overtravel of the member 91 to insure proper engagement of the latch 103 with the roller 101. It will be noted that the construction of the operating mechanism is such that the movable contact means is trip-free of the operating member 91; that is, when the breaker is tripped, the contact means move to open position irrespective of the position of the operating member 91.

The mounting arrangement of the contact means is such that during opening of the breaker the main bridging member 55 is first separated from the stationary contacts 25 and 27, while the auxiliary contacts remain in engagement by reason of the outward movement of the contact platform 33 under the influence of the biasing springs 41 and 43. After the bridging member 55 has separated a predetermined distance from the main stationary contacts, the intermediate contacts 29 and 69 begin to separate. This takes place as soon as the pins 35 engage the ends of the slots 37. During this time, the arcing contacts 31 and 71 remain in engagement due to the rocking movement of the contact platform 33. After the intermediate contacts have separated a predetermined distance, the arcing contacts 31 and 71 begin to separate. During closing, the contacts engage in the reverse order, as will readily be understood. It will thus be seen that the arc formed during separation of the contacts is drawn only between the arcing contacts 31 and 71.

The circuit breaker is adapted to be tripped open either manually, or automatically, in response to predetermined overload conditions in the circuit, by means of a trip device indicated generally at 115.

The trip device comprises a trip lever 117 which is pivotally mounted intermediate its ends on the frame 79 by means of a pivot pin 119, and an electromagnetic trip means, indicated generally at 121, which is operable in response to the predetermined overload conditions to move the trip lever 117 to tripping position to cause automatic opening of the circuit breaker.

One arm 123 of the trip lever 117 is offset and extends inwardly toward the base 11 of the circuit breaker, and has its inner end disposed immediately above the trip means 121 to be engaged and moved by a plunger of the electromagnet to effect automatic tripping of the breaker. The arm 123 of the trip lever is provided with a projection 125 which is adapted to engage the curved tailpiece 105 of the auxiliary latch 95 to move this latch to released position upon movement of the trip lever to tripping position. The other arm 127 of the trip lever 117 forms a handle whereby

the trip lever may be manually moved to tripping position to effect manual opening of the circuit breaker. A spring 129 connects the arm 123 of the trip lever 117 to an extension of the main holding latch 103 so that the spring thus serves to bias the main holding latch to latching position and the trip lever to its normal inoperative position, as shown in Fig. 1.

The electromagnet 121 comprises a U-shaped magnetic yoke member 131, a movable armature 133 having a trip rod 135 thereon, an energizing winding 137 having one end connected to the contact block 23 and the other end connected to the terminal 15, a time delay device illustrated generally at 139, and a shockproof device indicated generally at 141.

The ends of the U-shaped magnet yoke 131 are formed over adjacent the base 11 and are secured thereto by screw bolts 143 and 145, the bolt 143 also serving to secure the lower end of the contact block 23 to the base. A magnetic pole piece 147 threadedly engages an opening in the upper leg of the magnet yoke 131 and is locked in position by a lock nut 149. The pole piece 147 is provided with a central opening through which the trip rod 135 extends.

The armature 133 comprises an instantaneous trip armature 151 to which the trip rod 135 is secured and a time delay trip armature 153. The instantaneous trip armature comprises a cylindrical member of magnetic material closed at the upper end by a cap 155 also of magnetic material which threadedly engages the trip rod 135 as well as the cylinder 151. A washer 157 of non-magnetic material is rigidly secured to the upper face of the cap 155 as by brazing. A member 159 of non-magnetic material is provided with a flange 161 which threadedly engages the reduced upper end of the time delay armature 153 and a spring 163 is compressed between the flange 161 and an inwardly extending flange 165 on the lower end of the instantaneous trip armature 151. A washer 167 of non-magnetic material surrounds the armature 153 and is disposed between the bottom of the armature 151 and a shoulder on the armature 153 so that upward or tripping movement of the time delay armature 153 causes the instantaneous trip armature 151 and the trip rod 135 to move therewith, but permits tripping movement of the instantaneous tripping armature 151 and the trip rod 135 independently of the time delay armature 153 by compressing the spring 163.

The time delay device 139 comprises a pair of separable suction discs 169 and 171 of non-magnetic material disposed in a hermetically sealed casing comprising an upper portion 173 and a lower portion 175 both of non-magnetic material. The lower end of the upper casing 173 is reduced in diameter and is telescoped into the lower portion 175. This joint is sealed by brazing or soldering. The lower disc 169 is disposed in the casing below the shoulder formed by the reduced portion of the upper casing 173 which limits the axial movement of the lower disc. The lower suction disc 169 is supported on a spherical bearing 177 to provide for accurate alignment of the faces of the discs when the device is reset.

The upper disc 171 is slidably disposed within the reduced lower portion of the upper casing 173 and has a very slight clearance so as to act as a piston. The upper disc 171 is biased downward into contact with the lower disc 169 by means of a conical coil spring 179. After the casing

173-175 is hermetically sealed, it is filled to a predetermined level with oil or liquid silicone of a suitable viscosity through an opening (not shown) which opening is then also hermetically sealed. The engaging surfaces of the discs 169 and 171 are lapped smooth and flat so as to form an oil seal therebetween when the discs are pressed into engagement by the spring 179. The upper casing 173 has a reduced portion 181 which extends upwardly through an opening in the lower leg of the magnet yoke into the lower turns of the coil 137. The portion 181 of the casing is shaped downwardly as at 183 to form a cupped portion to receive the enlarged lower end of the armature 153.

A cup-shaped armature 185 of magnetic material is rigidly secured in a counter bore in the upper face of the upper suction disc 171. The member 185 may be secured to the disc 171 by any suitable means such, for instance, as brazing. Extending vertically through the bottom of the member 185 and also through the disc 171 are openings or passages 187 which are normally closed by means of a check valve 189 in the form of a disc. Horizontally disposed passages 191 through the side wall of the cup-shaped member 185 are provided to complete the passage to permit displacement of fluid to complete the passages to permit displacement of fluid from below the disc 171 during a resetting operation.

Extending between the bottom of the cup-shaped depression 183 and the bottom of the lower casing 175 is a tube 193 through which the trip rod 135 extends. The tube 193 is secured to both casing portions 173-175 so as to form a hermetic seal preferably by soldering or brazing. The trip rod extends below the dashpot and has an enlarged lower end in which is mounted a pin 195, the ends of which extend into openings in arms 197 of a U-shaped lever 199 one arm of which lever is disposed on each side of the trip rod. The lever 199 is pivoted on a pin 201, the ends of which are supported in spaced angular brackets 203 (Fig. 2) mounted by means of screws 205 on the lower leg of the magnet yoke 131. It will be noted that the dashpot is mounted between the brackets 203 and the magnet yoke and is supported in the position shown by the brackets 203 and screws 205.

A spring 207 is provided to bias the lever 199 in a counterclockwise direction thereby biasing the movable core structure against operation. The spring 207 has one end anchored to the yoke portion 209 of the lever 199 and the other end of the spring is anchored to an adjustable stud 211 movable vertically in a slot 213 in a scale plate 215 attached by means of screws 216 to the magnet yoke 131 and to the brackets 203. A thumb nut 217 threadedly engages the stud 211 to clamp it in the adjusted position. A clamp member 219 which has formed over portions engaging the slot 213 to hold it in vertical position is provided with a pointer 221 (Fig. 2) which cooperates with a scale indicated at 223 on the scale plate 215 to indicate the tripping point at which the device is adjusted.

By unloosening the thumb nut 217 and moving the stud 211 up or down the tension of the spring 207 may be varied thereby varying the minimum overload current required to trip the breaker.

Energization of the winding 137 creates a magnetic flux path from the lower leg of the magnet yoke 131 to the dashpot armature 185, across a high density flux path to the lower end of the time delay tripping armature 153, to the flange

165 of the instantaneous tripping armature 151, to the cap 155, across the air gap to the pole piece 147 and thence to the magnet yoke 131.

When the winding 137 is energized in response to a persistent overload current in the low range of overload currents of, for instance, up to 300% of normal rated value the magnetic force across the air gap 147—155 attracts the instantaneous trip armature 151 upwardly but, since this force is insufficient to compress the spring 163, the force is applied through the spring 163 to the time delay trip armature 153. It will be observed that the lower end of the time delay tripping armature 153 is concave and that the upper end of the cup shaped armature 185 is beveled and that the sharp edges of the armatures 153 and 185 lie in substantially a horizontal plane when these parts are in their normal position. These edges are shape to produce an extremely high magnetic flux density in the air gap 153—185, thus forming a magnetic coupling between the time delay tripping armature 153 and the armature 185 which is rigidly secured to the upper sucker disc 171. Due to the high density flux across the air gap 153—185, the armature 153 is prevented from immediate upward movement but the magnetic force is applied through the dashpot armature 185 to the upper suction disc 171. After a predetermined time delay, depending on the magnitude of the overload current, the oil seal between the suction discs 169 and 171 is broken, whereupon the entire movable core structure including the dash pot armature moves upwardly raising the trip rod 135 to trip the breaker. During the tripping movement, the cylindrical portion of the armature 185 moves into the annular space between the inner wall 183 and the outer wall 181 of the reduced portion of the upper casing 173 which extends into the winding.

After the seal between the suction discs 169—171 is broken the upward movement of the upper disc 171 is further delayed due to the fact that oil must be forced between the periphery of the disc 171 and the inner wall of the casing 173. This retarding action occurs up to the point when the disc 171 clears the reduced lower portion of the casing 173 at which time the space between the disc 171 and the casing 173 is increased and permits a free flow of oil and removes the restraint from the moving core structure which is then free to move rapidly upward to trip the breaker.

After the breaker contacts are opened and the winding 137 deenergized, the armatures 151 and 153 are restored to their unattracted position under the influence of gravity aided by the spring 207. The downward movement of the tripping armatures is completely independent of the position of the disc 171 and the dashpot armature 185. The disc 171 is restored by means of the spring 179. As the disc 171 moves downwardly, the pressure of the oil through the passages 187 raises the check valve 189 and permits free flow of oil through the passages 187 and 191 to the upper side of the disc 171 thus permitting quick resetting of the dashpot device and quickly reestablishes the seal between the suction discs.

Upon the occurrence of an overload in the intermediate range of overload currents, for example, between 300% and 1000% of normal rated current, the force is insufficient to compress the spring 163 but is large enough to cause the oil seal between the suction discs 169 and 171 to break with negligible time delay. The breaker

is tripped open on overloads in the intermediate range after a relatively short time delay occasioned by the plunger action of the upper disc 171 in the restricted portion of the casing 173.

5 Upon the occurrence of an overload above 1000% of rated current, or a short circuit, the instantaneous tripping armature 151 is attracted upwardly with such force that it compresses the spring 163 and moves to trip the breaker independently of the time delay armature 153 and without breaking the oil seal between the suction discs 169—171. When an overload above 1000% of normal current, or a short circuit occurs, the magnetic coupling between the armature 153 and the armature 185 attached to the suction disc 171 is increased to the point when the attraction of the instantaneous armature 151 overcomes the spring 163 and moves the armature 151 and the trip rod 135 independently of the armatures 153 and 185 to instantaneously trip the breaker. This sudden action does not break the magnetic coupling of the high flux density air gap 153—185 and does not break the oil seal between the discs 171 and 169. The armature 151 and the trip rod 135 are reset following an instantaneous tripping operation by the spring 163.

30 The limits of the intermediate range of overload currents (300% to 1000% of normal current) set forth are to be considered merely by way of example and these may be varied considerably to suit particular requirements. For instance, by the provision of stronger or weaker springs entirely different sets of values may be established.

35 The trip device is susceptible to sudden shocks delivered thereto in vertical direction and provision is made to prevent false tripping in response to such shocks or jarring forces. The means for preventing operation of the trip device in response to shocks comprises a lever 225 pivotally mounted on a pin 227 supported between the brackets 203. The lever 225 comprises two spaced parallel levers 226 which straddle the arms 197 of the U-shaped lever 199 and between them carry a mass 229 mounted on a pin 231. The ends of a spring 233 coiled about the pin 227 extend across the plane of the lever 225 and also across the plane of the vertical portion of one of the brackets 203 thus biasing the lever 225 and the mass 229 to a central position wherein pin 235, one end of which projects outwardly from each leg 197 of the U-shaped lever 199 are free to enter openings 237 in the ends of the levers 226 upon clockwise or tripping movement of the lever 199.

40 Upon the occurrence of a shock delivered to the trip device in vertical direction, the unbalanced mass 229 will cause the lever 225 to move in either clockwise or counterclockwise direction depending upon the direction of the shock thus moving the right hand end of the lever into the path of clockwise movement of the pins 235 to block tripping movement of the lever 199 and of the trip rod 135.

45 Having described the invention in accordance with the patent statutes, it is to be understood that various changes and modifications may be made in the structural details and combination of elements disclosed without departing from some of the essential features of the invention.

50 I claim as my invention:

55 1. In a circuit breaker comprising relatively movable contacts and operating means therefor, an electromagnet operable to cause automatic

operation of said operating means including an energizing winding, a sealed chamber mounted in fixed relation to said electromagnet, a first armature disposed externally of said chamber and movable upon energization of said winding to cause tripping of said breaker, a time delay device operable under certain circuit conditions to delay tripping movement of said armature comprising a pair of separable suction discs disposed in said sealed chamber, and a second armature disposed in said sealed chamber and attached to one of said suction discs for restraining tripping operation of said first armature.

2. In a circuit breaker comprising relatively movable contacts and operating mechanism therefor, a trip mechanism operable to cause automatic operation of said operating mechanism, a fixedly mounted sealed chamber containing a body of fluid, an electromagnet comprising a movable core structure disposed externally of said chamber and movable upon energization of said electromagnet to actuate said trip mechanism, time delay means for delaying tripping movement of said movable core structure comprising a suction disc disposed in said sealed chamber for delaying operation of said movable core structure, and an armature attached to said suction disc and disposed in said sealed chamber cooperating with said movable core structure upon energization of said electromagnet to form a magnetic air gap for restraining said core structure against tripping movement.

3. In a circuit breaker comprising relatively movable contacts and operating means therefor, a trip device operable to cause automatic operation of said operating means comprising an energizing winding, a sealed chamber mounted in fixed relation to said winding, a tripping armature disposed within said winding but externally of said chamber and movable upon energization of said winding to effect tripping of said breaker, time delay means comprising fixed and movable suction discs disposed within said sealed chamber, and a second armature attached to said movable suction disc disposed within said sealed chamber and responsive to overload currents to magnetically couple said movable suction disc to said tripping armature to restrain tripping movement of said tripping armature.

4. In a circuit breaker comprising relatively movable contacts and operating means therefor, a trip device operable to cause automatic operation of said operating means comprising an energizing winding, a tripping armature disposed within said winding and operable to effect tripping of said breaker, a sealed chamber mounted in fixed relation to said winding, time delay means comprising fixed and movable suction discs disposed within said sealed chamber, a second armature disposed outside of said winding but within said sealed chamber responsive to energization of said winding to magnetically couple said movable suction disc to said tripping armature to restrain tripping operation of said tripping armature, and a third armature operable at times independently of said tripping armature to instantaneously trip the breaker.

5. In a circuit breaker comprising relatively movable contacts and operating means therefor, an electromagnetic trip device operable to cause automatic operation of said operating means comprising an energizing winding, a trip mem-

ber movable to effect tripping of said breaker, a first armature for actuating said trip member, a hermetically sealed chamber, a second armature disposed externally of said sealed chamber and operable in response to overload currents below a predetermined value to actuate said trip member, time delay means comprising a dashpot disposed within said sealed chamber for delaying tripping operation of said second armature, a third armature disposed in said sealed chamber responsive to energization of said winding by overload currents to magnetically couple said second armature to said dashpot, and said first armature being operable in response to overload currents above said predetermined value to instantaneously actuate said trip member independently of said second armature.

6. In a circuit breaker comprising relatively movable contacts and operating mechanism, an electromagnetic trip device operable to cause automatic operation of said operating mechanism, a fixedly mounted sealed chamber, said trip device comprising an energizing winding, a tripping armature disposed in said winding but externally of said chamber and movable upon energization of said winding to effect tripping of said breaker, time delay means for delaying tripping movement of said tripping armature comprising a dashpot disposed in said chamber for delaying operation of said tripping armature, and a second armature disposed within said sealed chamber attached to said dashpot for magnetically relating said dashpot to said tripping armature.

7. In a circuit breaker comprising relatively movable contacts and operating means therefor, a trip device operable to cause automatic operation of said operating means comprising an electromagnet having an energizing winding, a hermetically sealed dashpot mounted in fixed relation to said winding and having a portion extending into said winding, a movable core structure disposed within said winding but externally of said sealed dashpot, said movable core structure being operable upon energization of said winding to trip said breaker, and a magnetic element disposed within said sealed dashpot and forming a magnetic connection between said movable core structure and said dashpot to restrain said movable core structure against tripping operation.

8. In a circuit breaker comprising relatively movable contacts and operating means therefor, a trip device operable to cause automatic operation of said operating means comprising an electromagnet having an energizing winding, a hermetically sealed chamber mounted in fixed relation to said electromagnet and having a portion extending into said winding, fixed and movable suction members disposed in said sealed chamber, a movable armature having a portion nested within said portion of said chamber but disposed externally of said chamber and operable upon energization of said winding to effect tripping of said breaker, and a magnetic member attached to said movable suction member and disposed within said sealed chamber and forming a magnetic connection between said movable armature and said movable suction member for restraining said armature against tripping operation.

9. In a circuit breaker comprising relatively movable contacts and operating means therefor, a trip device operable to cause automatic operation of said operating means comprising an

electromagnet having an energizing winding, a fixed hermetically sealed chamber having a portion extending into said winding, fixed and movable suction members disposed in said sealed chamber, a movable armature disposed externally of said chamber and operable upon energization of said winding to effect tripping of said breaker, and a magnetic member disposed within said sealed chamber attached to said movable suction member and forming a magnetic coupling between said movable armature and said movable suction member for delaying tripping operation of said armature, said magnetic member in said chamber forming the sole coupling between said movable suction member and said externally disposed armature.

10. In a circuit breaker comprising relatively movable contacts and operating means therefor, a trip device operable to cause automatic operation of said operating means comprising an electromagnet, an energizing winding, a fixedly mounted sealed chamber, a trip rod extending axially through said winding and said sealed chamber, a first armature disposed in said winding and secured to said trip rod and operable in response to certain circuit conditions to actuate said trip rod to trip the breaker, a second armature operable in response to certain other circuit conditions to operate said first armature to trip the breaker, a dashpot disposed in said sealed chamber for at times delaying operation of said second armature, and a magnetic member disposed in said sealed chamber for magnetically relating said dashpot to said second armature.

11. In a circuit breaker comprising relatively movable contacts and operating means therefor, a trip device operable to cause automatic operation of said operating means comprising an electromagnet, an energizing winding, a fixedly mounted sealed chamber, a trip rod extending axially through said winding and said sealed chamber, a first armature secured to said trip rod and operable in response to certain circuit conditions to actuate said trip rod to trip the breaker, a second armature operable in response to certain other circuit conditions to operate said first armature to trip the breaker, said first and said second armatures being disposed externally of said sealed chamber, a dashpot disposed in said sealed chamber for at times delaying operation of said second armature, and a magnetic member disposed in said sealed chamber for magnetically relating said dashpot to said second armature.

12. In a circuit breaker comprising relatively movable contacts and operating means therefor, a fixedly mounted sealed chamber, a trip device operable to cause automatic operation of said operating mechanism comprising an electromagnet having an energizing winding, a tripping armature disposed externally of said chamber and movable upon energization of said electromagnet to effect tripping of the breaker, time delay means comprising a fixed suction member in said sealed chamber, and a movable suction member in said sealed chamber magneti-

cally related to said tripping armature and cooperating with said fixed suction member to form a seal for restraining said armature against tripping operation, said chamber having a portion cooperating with said movable suction member after said seal is broken to provide additional time delay.

13. In a circuit breaker comprising relatively movable contacts and operating means therefor, a fixedly mounted sealed chamber containing a body of oil, a trip device operable to cause operation of said operating means comprising an electromagnet having a movable armature disposed externally of said chamber and operable upon energization of said electromagnet to effect tripping of said breaker, time delay means comprising a fixed suction member disposed within said chamber, a movable suction member magnetically related to said externally disposed armature and cooperating with said fixed suction member to form an oil seal to delay operation of said armature, said seal delaying tripping operation of said armature for a relatively long time delay, said chamber having a portion cooperating with said movable suction member after said seal is broken to delay tripping operation of said armature for a relatively short time delay, and a member movable in response to shocks for blocking tripping operation of said armature in response to sudden shocks or jarring forces.

14. In a circuit breaker comprising relatively movable contacts and operating mechanism therefor, a trip member operable to cause automatic operation of said operating mechanism, a trip device including an electromagnet, a fixedly mounted sealed chamber, a fixed magnetic member supporting said sealed chamber, a first armature disposed externally of said sealed chamber and movable upon energization of said electromagnet to actuate said trip member, time delay means for delaying operation of said armature comprising a dashpot disposed in said chamber, and a second armature disposed in said chamber and connected to said dashpot, said second armature cooperating with said first armature to form an air gap of high density flux forming a magnetic coupling between said armatures for restraining said first armature against movement to thereby delay tripping movement of said first armature.

OSWALD von MEHREN.
